Attorney

UNITED STATES PATENT OFFICE.

MATTIE COX BARRON, OF NEBO, KENTUCKY.

IRONING BOARD.

Application filed July 28, 1923. Serial No. 654,389.

To all whom it may concern:

Be it known that I, MATTIE C. BARRON, a citizen of the United States, residing at Nebo, in the county of Hopkins and State of Kentucky, have invented certain new and useful Improvements in Ironing Boards, of which the following is a specification, reference being had to the accompanying drawings.

10 This invention relates to ironing boards and more particularly to a mounting for ironing boards.

An important object of the invention is to provide a mounting for an ironing board 15 upon which the ironing board while permanently mounted is rotatable so that either surface thereof may be brought into use.

A further object of the invention is to provide a device of this character which 20 when not in use may be compactly and flatly folded for storage.

These and other objects I attain by the construction shown in the accompanying drawings, wherein for the purpose of illustration is shown a preferred embodiment of 25 my invention and wherein:—

Figure 1 is a perspective view of an ironing board constructed in accordance with my invention;

30 Figure 2 is a fragmentary sectional view taken therethrough; and

Figure 3 is a side elevation showing the board in folded position.

Referring now more particularly to the 35 drawings, the numerals 10 and 11 indicate pivotally connected leg sections. The leg section 11 is provided at its upper end with an iron support 12 and adjacent this upper end with a transversely extending mem-

ber 13 connecting the legs of the sections and pivotally engaged therewith so that it 40 is rotatable between the leg sections. With the central portion of this transverse member 13 the central portion of one end of a

45 board 14 is pivotally connected, as at 15, for rotation upon its longitudinal axis so that either surface of the board may be arranged uppermost. The opposite end of the board is provided upon opposite faces 50 thereof with similarly positioned stop members 16 adapted for coaction with a cross member 17 formed upon the upper end of

the other of the leg sections 10. The leg sections 10 and 11 may be suitably braced, as at 18, if so desired.

The cross member 13, being pivoted upon a horizontal axis between the legs of the section 11, may be rotated upon its axis by engagement of the board to free the stop member 16 of the lower side of the board 55 from the transverse member 17 connecting the upper ends of the legs of the leg section 10. When the board is free from the transverse member 17 it may be rotated from the longitudinal axis to place the under surface thereof uppermost for use. It 60 will, of course, be understood that the board will be provided with the usual padding and covering upon each face thereof. By the use of a device of this character the 65 necessity for changing the cover of the board so frequently is eliminated and if one surface of the board be scorched and accordingly unfit for use in ironing fine dress goods the other surface may be brought into 70 use for this purpose. When the work is finished the device may be folded by simply elevating the free end of the board 14 and collapsing the leg sections which lie in flatly 75 folded relation, the board resting thereon. 80 When thus folded, a clearly shown in Figure 3 the device is very compact and may be readily stored.

It will, of course, be obvious that certain 85 changes and modification of the structure may be resorted to without in any manner departing from the spirit of my invention and I accordingly do not limit myself to such specific structure as hereinbefore set forth except as hereinafter claimed.

I claim:—

In combination with an ironing board, a support therefor having means engaging opposite ends of the board to support the same, said means at one end of the board 95 including a member mounted for rotation upon a horizontal axis extending transversely of the board and with which the board is pivotally engaged at its longitudinal axis.

100 In testimony whereof I hereunto affix my signature.

MATTIE COX BARRON.
